CLAIM

The ornamental design for a sports glove, as shown and described.

DESCRIPTION

FIG. 1 is a top perspective view of the sports glove of the present invention;

FIG. 2 is a plan view of the dorsal side of the sports glove;

FIG. 3 is a plan view of the palmar side thereof;

FIG. 4 is a top view of the sports glove;

FIG. 5 is a bottom view of the sports glove;

FIG. 6 is a left side view of the sports glove;

FIG. 7 is another left side view of the same sports glove; and,

FIG. 8 is a right side view of the present invention.

The logo outlined by broken lines on the sports glove defines a feature of the article that forms no part of the claimed design. The dot-dot broken lines along the surfaces of the sports glove depict feature lines of the article that form no part of the claimed design. The dash-dot broken line in FIG. 5 defines the bounds of the claimed design and form no part thereof.
